DESCRIPTION

FIG. 1 is a perspective view of a sterilizer showing my new design;

FIG. 2 is a perspective view thereof with the sterilizer in its open position;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the sterilizer that form no part of the claimed design.
